Primary Examiner — Jennifer Rivard*Assistant Examiner* — April Rivas(74) *Attorney, Agent, or Firm* — Ulmer & Berne LLP(57) **CLAIM**

The ornamental design for a display case, as shown and described.

DESCRIPTION

FIG. 1 is a front perspective view of the first embodiment of a display case;

FIG. 2 is a front elevational view of the display case of FIG. 1;

FIG. 3 is a rear elevational view of the display case of FIG. 1;

FIG. 4 is a left side elevation view of the display case of FIG. 1;

FIG. 5 is a right side elevation view of the display case of FIG. 1;

FIG. 6 is a top plan view of the display case of FIG. 1;

FIG. 7 is a bottom plan view of the display case of FIG. 1; and,

FIG. 8 is a front perspective view of a second embodiment of the display case showing a stacked pair.

The broken lines in the figures illustrate unclaimed portions of the display case.
